OR D 14,489

No. 14,489

DEC 18, 1883

UNITED STATES PATENT OFFICE.

H. CLAY BASCOM AND CYRUS A. HODGES, OF TROY, N. Y., ASSIGNEES TO N. S. VEDDER PATTERN WORKS, BASCOM, GALBRAITH & CO., OF SAME PLACE.

DESIGN FOR A PARLOR-STOVE.

SPECIFICATION forming part of Design No. 14,489, dated December 18, 1883.

Application filed November 7, 1883. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Parlor-Stoves, of which the following is a specification, reference being had to the accompanying cut, 10 print, or engraving, representing our said new design.

The design for the crest-plates A consists of the lower portion, *a*, and upper portion *b*, combined, shaped, and ornamented substantially as shown in the aforesaid print.

The design for the vase B consists of the lower concavely-curved stem part, *c*, upper flaring portion *d*, having a series of pointed arch apertures, and the intermediate concave-20 ly-flaring part, *e*, having a series of upwardly-enlarged apertures with angular tops, all shaped and combined substantially as shown in the aforesaid cut.

The design for the central dome-shaped 25 cap part, C, consists of the lower band, *f*, upper band, *g*, and wider intermediate curved portion, *h*, having the lower series of upwardly-tapering apertures alternating with a series of upper downwardly-tapering openings, all shaped and arranged together substantially as shown in the aforesaid engraving.

The design for the upper sliding doors, D, 30 consists of the compound panel ornament *i*, shaped and arranged upon the raised quadrilateral panel-surface *j*, substantially as shown in the accompanying representation.

The design for the upper front plate, E, 35 consists of the ornamental bands *k*, arranged in and obliquely across the round top oblong panel, *l*, substantially as shown.

The design for the middle band-plate, F, 40 consists of the oblong central tablet, *m*, and the rectangular end parts, having thereon the ornaments *n*, shaped and arranged as shown.

The design for the lower sliding doors, G, 45 consists of the compound vine and floral ornamentation *o*, shaped and arranged upon and diagonally across the raised quadrilateral panel-surface *p*, substantially as shown.

The design for the lower front plate, H, 50 consists of the ornamental bands *q*, shaped and arranged in and obliquely across the oblong rectangular panel-surface *r*, substantially as shown.

The design for the end door, I, consists of 55 the compound vine and flower ornament *s*, shaped and arranged upon and obliquely across the round top panel-surface, *t*, having the ornamental border *u*, as shown.

The design for the end plate, J, consists of 60 the arched ornamental *v* and *w*, composed and arranged together as shown.

The design for the legs consists of the ornament *x* on the upper portion, *y*, and the ornament *z* on the convex lower portion, *z'*, all 65 shaped and arranged substantially as shown.

We claim as our invention—

1. The design for the crest-plates A, composed of the parts *a* and *b*, shaped and ornamented as set forth.

2. The design for the vase B, composed of 70 the parts *c d e*, shaped and arranged together as shown and described.

3. The design for the central cap part, C, 75 consisting of the parts *f g h*, shaped and arranged together as shown and described.

4. The design for the doors D, composed of the parts *i j*, shaped and arranged as shown and described.

5. The design for the upper front plate, E, 80 composed of the parts *k l*, shaped and arranged together as shown and described.

6. The design for the middle band-plate, 85 F, composed of the parts *m n*, shaped and arranged as shown and described.

7. The design for the doors G, composed of the parts *o p*, shaped and arranged as set forth.

8. The design for the lower front plate, H, 90 consisting of the parts *q r*, shaped and arranged as shown and described.

9. The design for the end door, I, composed of the parts *s t u*, shaped and arranged as described.

10. The design for the end plate, J, composed of 95 the parts *v w*, shaped and arranged together as shown and described.

11. The design for the legs, composed of the parts *x y z z'*, as shown and described.

In testimony whereof we hereunto set our 100 hands, in the presence of two subscribing witnesses, this 5th day of November, 1883.

H. CLAY BASCOM.
CYRUS A. HODGES.
